(57) **CLAIM**

The ornamental design for an automated teller machine as shown and described.

DESCRIPTION

FIG. 1 is a front, top and right side perspective view of an automated teller machine according to the design;

FIG. 2 is a front, top and left side perspective view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear elevational view thereof;

FIG. 9 is an enlarged view of the portion shown in the dot-dash line box labeled FIG. 9 in FIG. 1;

FIG. 10 is an enlarged view of the portion shown in the dot-dash line box labeled FIG. 10 in FIG. 1;

FIG. 11 is a cross-sectional view taken along line 11-11 of FIG. 3;

FIG. 12 is a cross-sectional view taken along line 12-12 of FIG. 3;

FIG. 13 is a cross-sectional view taken along line 13-13 of FIG. 3;

FIG. 14 is an enlarged view of the portion shown in the dot-dash line box labeled FIG. 14 in FIG. 13; and,

FIG. 15 is another front, top and right side perspective view thereof, shown in a used condition with environmental structure shown in broken lines.

The evenly spaced dash lines represent environmental subject matter that forms no part of the claimed design. The dot-dash line boxes shown in FIGS. 1 and 13 define the enlarged portions shown in FIGS. 9-10 and 14, and form no part of the claimed design.
